UNITED STATES PATENT OFFICE

CHARLES WALKER, OF KNOXVILLE, TENNESSEE

VENDING MACHINE

Application filed June 3, 1931. Serial No. 541,791.

My invention consists in new and useful improvements in vending machines and has for its object to provide a device of this character particularly adapted for use in combination with a filling station pump or the like for vending gasoline, motor oils and other liquids.

Another object of my invention is to provide a coin controlled mechanism whereby varying quantities of liquids may be obtained by the purchaser upon the insertion of coins of the proper denominations.

A still further object of the invention resides in the structure whereby the machine may be employed at times as an ordinary filling station pump while at other times, in the absence of an attendant, it may be used as a coin controlled vending machine.

With the above and other objects in view which will appear as the description proceeds, my invention consists in the novel features herein set forth, illustrated in the accompanying drawing and more particularly pointed out in the appended claims.

Referring to the drawing in which numerals of like character designate similar parts throughout the several views,

Fig. 1 is a front elevation of the device partially broken away and partially in section.

Fig. 2 is a top plan view of the same partially broken away.

Fig. 3 is a fragmentary sectional view taken on line 3—3 of Fig. 2.

Fig. 4 is a sectional view taken on line 4—4 of Fig. 2, and

Fig. 5 shows a fragmentary view of the machine with an attachment whereby the device may be employed as an ordinary filling station pump.

In the drawing, 1 represents a casing within which is provided a horizontal platform 2 carrying a pair of upright supports 3. 4 represents a longitudinally disposed shaft 45 which is rotatably mounted in suitable bearings 5 carried by the supports 3, one end of said shaft extending through the adjacent end wall of the casing 1 and being provided with a handle 6 whereby said shaft may be rotated in the bearings 5. The opposite end

of the shaft 4 is provided with a central annular opening 7 adapted to receive one end 8 of a crank arm 9, the other end 10 of which is operatively connected to the upper extremity of the pump rod 11 of a filling station pump or the like not shown. 55

A substantially V-shaped segment 12 is preferably cut out of one side of the shaft 4 adjacent the annular opening 7, said cut out portion being adapted to cooperate with a lug or projection 13 rigidly secured to the end 8 of the crank arm 9, and lying within the cut out portion 12, whereby a predetermined amount of play is permitted between the rotation of the shaft 4 and its operative engagement with the crank arm 9 as herein-after set forth more in detail.

At suitable points intermediate the ends of the shaft 4 I provide a plurality of coin receiving recesses or slots 14, 15 and 16, each 70 of which is located immediately below and in line with a coin chute 17, 18 and 19 respectively, said chutes and recesses being of varying sizes to receive coins of different denominations. For example, the recess 14 is 75 of a size to accommodate a five-cent piece and is arranged longitudinally of the shaft 4. The recess 15 is for convenience, arranged transversely of the shaft 4 and is of a size to accommodate a ten-cent piece. The recess 16, like the first named recess is arranged longitudinally of the shaft and is adapted to receive a twenty-five-cent piece. It will be understood of course that the respective coin 80 chutes are of a size corresponding to the size 85 and denomination of the coin to be inserted.

As shown in Fig. 2, immediately behind the shaft 4 I provide a series of coin engaging levers 20, 21 and 22, pivoted at one end on suitable bearings 23, 24 and 25 respectively. 90 Each of these levers is provided with a projecting lugs 20¹, 21¹ and 22¹ respectively, which extends toward the shaft 4 and terminates within a short distance therefrom, 95 in line with the arc described by a coin in the corresponding slot in the shaft upon the rotation of said shaft.

Each of the levers is operatively connected at its free end to the adjacent lever, the end 100

of the lever 20 being slidably connected to the intermediate portion of the adjacent lever 21 by means of a pin 26 in the latter which lies within and engages a vertical slot 27 in the hook-like end of the lever 20, whereby upon the rearward movement of the lever 20 upon its pivot 23, the lever 21 will in turn be swung rearwardly a predetermined distance on its fulcrum, yet upon the rearward movement of the lever 21, the pin 26 will ride freely within the slot 27 without effecting the rearward movement of the lever 20. Likewise the free end of the lever 21 is slidably connected to an intermediate point on the lever 22 by means of a similar pin 28 in the latter which lies within and engages the vertical slot 29 in the hook-like end of the lever 21. Thus upon the rearward movement of the lever 20 or the lever 21, the lever or levers posterior thereto will be caused to swing on their pivots a corresponding degree, while upon the movement originating with either of the levers 21 or 22, the levers anterior thereto will not be effected.

25 Each of the levers just described is normally retained in position adjacent the shaft 4 by suitable springs 30 as will be clearly seen in Fig. 2.

30 31 represents a suitable platform or the like which lies just behind the shaft 4 and extends transversely therefrom, said platform being provided with suitable guideways 32 adapted to slidably support a rack member 33. The rack member 33 is provided on its underface with a series of downwardly projecting teeth 34 which lie within a slot extending longitudinally of the platform 31, said teeth being adapted to cooperate with a pinion lever 35 fulcrumed at a point intermediate its ends to a suitable support 36. The pinion lever is provided on one side of its fulcrum with an upwardly projecting tooth 37 which is normally retained in engagement with the adjacent tooth of the rack bar 33 by means of a spring 38 which rocks the pinion lever on its fulcrum in clockwise direction, and the end 39 of the pinion lever terminates adjacent the rotary shaft 4 for the purpose hereinafter set forth. The opposite end of the pinion lever is provided with an upwardly projecting tooth 40 which is adapted to engage the adjacent tooth on the rack bar 33, upon the counter-clockwise rotation of the pinion lever on its fulcrum.

35 The end of the rack bar 33 adjacent the shaft 4 is bifurcated as at 41 and receives the end of the lever 22 which abuts the inner extremity of the bifurcation as shown in Fig. 3, said rack bar being normally forced toward the shaft 4 and into engagement with the lever 22 by a suitable spring 43. The underside of the bifurcation 41 forms a stop or abutment 44 which is adapted to contact with a stop member 45 on the shaft 4,

said stop 45 being so located on the periphery of the shaft 4 as to engage the abutment 44 before the rotation of said shaft has caused the operation of the pump rod 11.

46 represents a trip lug which is arranged in line with the end 39 of the pinion lever 35, whereby upon the rotation of the shaft 4 a predetermined distance, said lug will engage the end 39 of the pinion lever to release the tooth 37 from the adjacent tooth 34.

The operation of the device just described is as follows:

Should one attempt to operate the machine without first inserting a coin in one of the slots in the shaft 4, upon turning the handle 6 the stop lug 45 would come in contact with the stop or abutment 44 on the rack bar 33 prior to the engagement of the wall of the V-shaped notch 12 in the end of the shaft 4, with the lug or projection 13 on the end of the crank arm 9, and thus the machine would be prevented from causing the operation of the pump. Upon release of the handle it would return by gravity to its former position.

Now, upon the insertion of a five-cent piece in the slot 14, the rotation of the shaft 4 would bring this coin into engagement with the projection 20¹ on the lever 20, whereupon the continued rotation of the shaft 4 would cause the lever 20 and in turn the levers 21 and 22 to be rocked rearwardly on their fulcrums with the result that the rack bar 33 would be moved rearwardly to the extent of one tooth, thus moving the abutment 44 from the path of rotation of the stop 45 to permit one complete revolution of the shaft 4. When the trip lug 46 arrives adjacent the end 39 of the pinion lever, it rocks the same on its fulcrum 36 and releases the tooth 37 from the tooth 34, permitting the return of the rack bar 33 to its normal position by means of the spring 43, the abutment 44 being again in position to prevent a second rotation of the shaft 4.

Should a ten-cent piece be inserted in the slot 15 in the shaft 4, the rotation of the shaft would cause the coin to abut the projection 21¹ on the lever 21, whereupon the levers 21 and 22 would be rocked rearwardly on their fulcrums to such an extent that the end of the lever 22 would slide the rack bar 33 rearwardly for a distance of two teeth. Thus upon the first rotation of the shaft 4, the trip lug 46 would rock the pinion lever 35 on its fulcrum to release the tooth 37 from the tooth 34, but in this operation, the tooth 40 on the end of the pinion lever would engage one of the adjacent teeth 34 on the pinion lever to permit the return of said rack bar only for the distance of one tooth, the second rotation of the shaft 4 again tripping the pinion lever to return the rack bar to its normal position.

In a similar manner the insertion of a twenty-five-cent piece in the slot 16 would, through the medium of the lever 22, slide the rack bar rearwardly for a distance of five teeth and upon each rotation of the shaft 4 said rack bar would be returned successively for the distance of one tooth, towards its normal position.

In Fig. 5 I have shown a modification whereby this vending machine may be employed as an ordinary filling station pump. In this figure the end wall of the casing 1 adjacent the rack bar 33 is provided with a graduated dial 47 having suitable marks or indicia around its face. An indicator or pointer 48 is mounted on a short shaft 49 projecting through the center of the disc 47 and being operatively connected to a toothed collar or gear 50 within the casing 1 and immediately above and in line with the rack bar 33. The upper face of the rack bar 33 is provided with a series of longitudinally arranged teeth 51 which are adapted to mesh with the teeth of a collar or gear 50, and the outer end of said rack bar carries a laterally projecting shaft 52 which extends through the end wall of the casing 1 and slidably engages a slot 53 in said end wall. On the outer end of the shaft 52 I provide a nob or handle 54 which lies outside of the casing 1.

With this arrangement a station attendant or operator by grasping the nob 54 slides the rack bar 33 rearwardly which in turn causes the indicator 48 to rotate in counter-clockwise direction. Each of the graduations or marks on the dial 47 represents a predetermined quantity of gasoline or liquid which will be delivered upon the rotation of the handle 6 and thus if the rack bar 33 is drawn rearwardly until the indicator 48 points to the numeral 5, this indicates that said rack bar has been retracted for a distance of five of the teeth 34. The handle 6 is then turned and the remainder of the operation is identical with that heretofore described in connection with the coin actuated control, each complete rotation of said handle causing the rack bar 33 to successively return for a distance of one tooth until it has again reached its normal position.

Obviously, when the device is to be used as a coin controlled vending machine, the nob 54 is either removed or encased and locked so as to prevent the operation of the rack bar except by the insertion of a coin.

While I have shown and described this vending machine for use in vending liquids, it is obvious that the principle of operation may be applied with equal effect to a machine for vending articles or packages.

From the foregoing it is believed that the construction and operation of my improved vending machine may be readily understood

by those skilled in the art without further description, it being borne in mind that numerous changes may be made in the details disclosed without departing from the spirit of the invention as set forth in the following claims.

What I claim and desire to secure by Letters Patent is:—

1. In a coin controlled mechanism, the combination with a rotary member and means for rotating the same, of a movable stop element for controlling the rotation of said member, selective coin controlled mechanism including a series of interconnected levers for actuating said stop element to a predetermined position to permit a desired number of rotations of said rotary member, at least one of said levers being independently operable by a single coin, all of said levers being collectively operable in selected groups by single coins, and means for automatically returning said stop element to its normal position upon the last rotation of said rotary member.

2. In a coin controlled mechanism, the combination with a rotary member and means for rotating the same, of a movable stop element for controlling the rotation of said member, selective coin controlled mechanism including a series of interconnected levers for actuating said stop element to a predetermined position to permit a desired number of rotations of said rotary member, at least one of said levers being independently operable by a single coin, all of said levers being collectively operable in selected groups by single coins, and means actuated by said rotary member for automatically returning said stop element step by step to its normal position.

3. A vending machine comprising a casing, a shaft rotatably mounted in said casing, means for rotating said shaft, delivery means operatively connected to said shaft, said delivery means being adapted to vend a predetermined quantity of merchandise upon each complete revolution of said shaft, a rack bar slidably mounted adjacent said shaft and having a series of teeth arranged longitudinally thereon, stop means on said rack bar and complimentary stop means on said shaft for normally preventing the rotation of the latter, means for sliding said rack bar rearwardly away from said shaft to release said stop means, a pinion lever mounted adjacent the teeth of said rack bar and adapted to retain said rack bar in a retracted position, trip means on said shaft for releasing said pinion lever upon each rotation of said shaft, and means on said pinion lever for preventing the return of said rack bar for a distance of more than one tooth, upon each rotation of said shaft.

4. A coin controlled vending machine comprising a casing, a shaft rotatably

mounted in said casing, means for rotating said shaft, delivery means operatively connected to said shaft, said delivery means being adapted to vend a predetermined quantity of merchandise upon each complete revolution of said shaft, a plurality of slots in said shaft adapted to receive individual coins of different denominations, said slots being of such a depth as to support said coins in projecting relation to the periphery of said shaft, a corresponding number of coin chutes in said casing for delivering the respective coins to said slots, a toothed member arranged adjacent said shaft and provided 10 with an abutment, a stop member on said shaft adapted to normally engage said abutment, a coin actuated element adjacent each of said coin slots in said shaft, and means for operatively connecting each of said elements to said toothed member, whereby upon rotating the shaft with a coin inserted in one of said slots, said toothed member will be moved with respect to said shaft to release said stop mechanism, a second toothed member 20 cooperating with said first named toothed member for controlling the number of rotations of said shaft, and a trip member on said shaft adapted to actuate said second toothed member.

25 5. A coin controlled vending machine comprising a casing, a shaft rotatably mounted in said casing, means for rotating said shaft, delivery means operatively connected to said shaft and adapted to vend a predetermined quantity of liquid upon each complete revolution of said shaft, a plurality of slots in said shaft adapted to receive individual coins of different denominations, said slots being of such a depth as to support 30 said coins in projecting relation to the periphery of said shaft, a corresponding number of coin chutes in said casing for delivering the respective coins to said slots, a rack bar mounted adjacent said shaft and 35 slidably transversely therefrom, stop means on said rack bar and complimentary stop means on said shaft for normally preventing the rotation of the latter, means actuated by a coin in either of said slots for sliding said 40 rack bar away from said shaft to release said 45 stop means, a pinion lever mounted adjacent said rack bar and adapted to retain the latter in retracted position, trip means on said shaft for releasing said pinion lever upon each rotation of said shaft, and means on 50 said pinion lever for preventing the return of said rack bar for a distance of more than one tooth, upon each rotation of said shaft. 55 6. A coin controlled vending machine as claimed in claim 5 wherein said coin controlled means comprises a series of levers mounted adjacent said shaft, means on each of said levers for operatively engaging a coin in the respective coin slot, and means whereby the movement of any one of said levers is 60 transmitted to said rack bar. 7. A coin controlled vending machine as claimed in claim 5 wherein said coin controlled mechanism comprises a series of levers, pivotally mounted at one end, the other end of each lever being operatively connected to the lever next in line, the free extremity of the endmost lever being operatively connected to said rack bar, and means on each of said levers arranged adjacent one of said coin slots whereby upon the rotation of said shaft with a coin inserted in one of said slots, the movement of any one of said levers will be transmitted to said rack bar. 75 8. A vending machine as claimed in claim 3 including manually operated means for sliding said rack bar rearwardly away from said shaft to release said stop means. 9. A vending machine as claimed in claim 3 wherein the means for sliding said rack bar away from said shaft comprises a handle secured to the rack bar and extending through one wall of said casing. 100 10. A vending machine as claimed in claim 3 wherein the means for sliding said rack bar away from said shaft comprises a handle secured to the rack bar and extending through one wall of said casing, and an indicator operatively connected to said rack bar for gauging the extent of movement of the latter and in turn the quantity of merchandise delivered. 105 In testimony whereof I have affixed my signature.

CHARLES WALKER. 115
